(57) **CLAIM**

I claim the ornamental design for a wall mounted shower panel set with slide bar, as shown and described.

DESCRIPTION

FIG. 1 is an exploded perspective view of a wall mounted shower panel with slide bar showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top view thereof; and,
FIG. 7 is a bottom view thereof.
